UNITED STATES PATENT OFFICE.

RICE E. GREGORY, OF OWENSBOROUGH, KENTUCKY.

DESIGN FOR A WHIFFLETREE.

SPECIFICATION forming part of Design No. 24,314, dated May 14, 1895.

Application filed March 5, 1895. Serial No. 540,665. Term of patent 14 years.

To all whom it may concern:

Be it known that I, RICE E. GREGORY, a citizen of the United States, residing at Owensborough, in the county of Daviess and State of Kentucky, have invented and produced a new and original Design for a Whiffletree, of which the following is a specification.

Reference is to be had to the accompanying drawings, in which—

10 Figure 1 represents a perspective view of a whiffletree embodying my new design. Fig. 2 is a cross-section on line 2 2 of Fig. 1, and Fig. 3 is a cross-section on line 3 3 of Fig. 1.

15 The leading features of my design consist in a whiffletree having its ends curved as at *a* and extending outward forming arms *a'* at an angle to the longer central part *b*, the arms terminating at each end in returned ends *c*,

and the central or main part *b*, having a concave or hollow *d* in its back edge which follows the curved lines of the whiffletree and terminates at points *e* inward from the returned ends *c*.

20 Minor features of my design consist in the arch *f* which bridges the depression *d* at the center of the whiffletree, the cylindrical figure *g* that crosses the said depression beneath the arch, and the curved forward surface *b'* of the central part *b*.

25 I claim—

30 The design for a whiffletree herein shown and described.

RICE E. GREGORY.
